JAMES B. HAMMOND AND CARL O. AXELSON, OF NEW YORK, N. Y.

TYPE-WRITING MACHINE.

SPECIFICATION forming part of Letters Patent No. 547,397, dated October 1, 1895.

Application filed August 17, 1892. Serial No. 443,306. (No model.)

To all whom it may concern:

Be it known that we, JAMES B. HAMMOND and CARL O. AXELSON, of New York, in the county and State of New York, have invented 5 a certain new and useful Improvement in Type-Writing Machines, of which the following is a specification.

This invention relates more particularly to 10 attachments for a type-writing machine for regulating the tension of the carriage-motor, and when this motor is the prime cause of the hammer-stroke action it is evidently desirable that an increase of power should be given to the blow of the printing-hammer by the same 15 movement by which the prime-motor is increased.

The object of the invention is, then, by a 20 simple operation to increase or diminish the strength or tension of the carriage-motor 25 spring and at the same time regulate the hammer tension. Thus it is obvious that an operator can easily adjust the tension for mani- 30 folding, vary the strength of impression, or compensate for a too feeble or too strong a 35 ribbon.

The invention can be attached to any Ham- 40 mond type-writer by simply tapping the rear spindle-bearing in the bed-plate.

We will describe a type-writing machine em- 45 bodying our improvement, and then point out the novel features in claims.

In the accompanying drawings, Figure 1 is 50 a rear elevation of a type-writing machine with certain parts omitted to more clearly 55 show our improvement. Fig. 2 is a horizontal section through the axis of the spring-barrel on an enlarged scale. Fig. 3 is a sectional detail. Fig. 4 shows the hammer-spring.

Referring by letter to the drawings, A des- 55 ignates the base of the machine, having the bed-frame A' supported thereon.

B designates a spring-barrel loosely mounted 60 on a spindle B², and having a toothed periphery engaging with the rack-bar a, at- 65 tached to the paper-carriage a', which is moved in one direction by the expansion of a motor-spring B' within the barrel B, the said 70 spring being retracted or wound by a return movement of the carriage a' in the usual 75 manner. The spring B' at its outer end is se- 80 cured to the inner side of the barrel B, as at b, and the inner end has a loose engagement

with the spring-spindle B³, so that said spindle may have a longitudinal movement relatively to the spring. As here shown the inner 55 end of the spring B' engages with a pin b', which is attached to a sleeve b², surrounding the spindle B³ within the barrel B. The pin b' extends through the sleeve b² into a longitudinal channel b³ in the spindle B³. By this 60 construction it will be seen that the sleeve and pin may be rotated with the spindle to adjust the tension of the spring, and at the same time the spindle will be free to move longitudinally relatively to the sleeve and 65 spring. At one side of the barrel B the spindle B³ has a bearing b⁴ in the bed-frame A', and at the other side of the barrel it has a bearing b⁵ in the bed-frame. One of these 70 bearings, as here shown the bearing b⁵, is pro- 75 vided internally with a screw-thread, and the spindle is provided with a screw-thread b⁶, engaging the screw-thread of the bearing. Obviously when the spindle is rotated to adjust the spring tension the threaded portions 75 will impart a longitudinal movement to the spindle.

We provide means for holding the spindle B³ as adjusted, here shown as consisting of friction-plates C C', which are loosely mounted 80 on the spindle B³ and are movable toward and from the bed-frame A' by the longitudinal movement of the spindle B³. The plate C is mounted directly on the spindle B³, abut- 85 ting against an annular shoulder c⁶, attached to the spindle, and has its lateral extensions or arms provided with hooked plates c, which extend underneath the bed-frame A' and prevent the rotation of the plates. The plate C' is loosely mounted on a sleeve c', which is 90 loosely mounted on the spindle B³, and has its inner end provided with an annular flange c², having a friction-bearing between leather, rubber, or similar washers c³, secured to the inner surfaces of the plates C C'. The plates 95 C C' are connected together by means of a screw c⁴ and a screw-bolt c⁵, and by manipu- 100 lating the screw-bolt c⁵ the frictional bearing of the plates may be adjusted. The sleeve c' at the outer side of the plate C' is provided with a ratchet-wheel D. This ratchet-wheel may be secured to the sleeve by means of a screw d. A plate D' is secured to the spindle B³ at the outer side of the ratchet-wheel D in

any desired manner, but preferably by means of a left-hand thread, as shown, so that the tension of the spring will have a tendency to tighten rather than loosen the plate. The 5 plate D' has a dog d' pivoted to it and held in contact with the ratchet-wheel by means of a spring d'', secured at one end to said plate and bearing at the other end upon the dog. The object of employing the dog and 10 ratchet is to relieve the spindle while winding from the influence of the friction-plates.

The spring B' is adjusted to a normal tension when the machine is set up in the factory; but an operator can adjust the tension to any 15 desired degree above the normal by rotating the spindle B² to the right by means of a key engaging with its angular outer end. It is desirable, however, to limit the degree of tension to which the spring may be subjected. 20 We therefore provide a stop, here shown as an arm d³ on the plate D', which will contact with a pin d⁴ on the base A, when the spindle shall have been rotated sufficiently to the right to bring the arm d³ in line with the pin d⁴. Of course it is understood that when the 25 spindle is rotated to the right it has an outward longitudinal movement and carries with it the plate D' and the friction devices. It is evident that the annular shoulder e⁶ coming 30 in contact with the bed-frame will operate as a stop to prevent a too extended movement of the spindle to the left or to reduce the spring tension below the normal.

The outward and inward movement of the 35 friction-plates serves to adjust the stroke of the printing-hammer E for the purpose of manifolding. The releasing, stop, and return mechanism for the hammer need not be described herein excepting that the releasing 40 and returning mechanism F is operated from the barrel B by means of the rack a engaging with a gear-wheel F' of the said mechanism. The hammer E has forwardly-extending arms e, attached to a rock-shaft E', which 45 has pivot-bearings e', adjustably engaging with the bed-frame A'. A spring E² serves to rock the shaft E to impart the stroke motion to the hammer E. This spring E² is secured at one end to the rock-shaft and is 50 coiled around the same, as shown at e². From the rock-shaft the spring extends rearward and has a downwardly-turned end e³, engaging over the outer surface of the plate C, as plainly shown in Fig. 4.

55 By an outward movement of the plate C, as before described, the downwardly-turned end e³ of the spring E² will move slightly upward with a cam-like motion and at the same time the tension of the spring will be increased 60 on the rock-shaft E', so that the rock-shaft will have a quicker and stronger motion imparted to it and thus increase the stroke of the hammer.

Having described our invention, what we 65 claim is—

1. In a typewriting machine, the combination with a carriage and a motor spring for

moving the same forward, of a normally stationary but adjustable spindle to which one end of said spring is connected, so that its 70 tension may be varied, as desired, and friction plates connected to said spindle and serving to hold the latter in any desired position of adjustment.

2. In combination with the movable carriage having a rack bar, of a spring barrel engaging with the rack a rotary and longitudinally movable spindle upon which the barrel is mounted and a spring within the barrel having a loose engagement at one end with 80 the spindle, substantially as specified.

3. In a type writing machine the combination with the movable carriage, having a rack, of the barrel engaging with the rack, the spring within the barrel, a rotary and longitudinally movable spindle supporting the barrel and to which the spring has a sliding connection, a threaded portion on said shaft engaging in a threaded bearing and friction plates for holding the spindle as adjusted, 90 substantially as specified.

4. In a type writing machine the combination with a movable carriage, having a rack, of a barrel engaging with the rack, a spring within the barrel, a rotary and longitudinally 95 movable spindle and a stop for limiting the movements of said spindle, substantially as specified.

5. In a type writing machine, the combination with the movable carriage, of a spring 100 and spring barrel for imparting a movement to said carriage, a rotary and longitudinally movable spindle for the spring, friction plates loosely mounted on the spindle and a dog and 105 ratchet wheel connection between the spindle and friction plates, substantially as specified.

6. In a type writing machine the combination with the carriage, of a spring and spring barrel for imparting a movement to the same, a rotary and longitudinally movable spindle 110 having a longitudinal groove, a pin extending from the inner end of the spring into the groove, and a friction device for holding the spindle as adjusted, substantially as specified.

7. In a type writing machine the combination with the carriage, the motor and the spindle, of the friction plates on the spindle and means for adjusting the friction, substantially 115 as specified.

8. In a type writing machine the combination with a carriage, a motor and the rotary and longitudinally movable spindle for the motor, of the friction device, consisting of the plates loosely mounted on the spindle, a sleeve 120 loosely mounted on the spindle and having a 125 flange extended between the plates, a ratchet wheel secured to the sleeve, a plate attached to the spindle and a dog pivoted to said plate and engaging with the ratchet wheel, substantially as specified.

9. In a type writing machine the combination with a carriage, of a motor therefor, a printing hammer, a spring for causing the stroke of said hammer, and means for chang- 130

ing the power of the motor and also regulating the hammer blow, substantially as specified.

10. In a type writing machine the combination with the carriage, the motor spring, the rotary and longitudinally movable spindle for the spring, friction devices on said spindle, a printing hammer and a spring for impelling the hammer, engaging at one end with said 10 friction devices whereby a longitudinal move-

ment of the spindle will adjust the tension of the hammer spring, substantially as specified.

In testimony whereof we have signed our names to this specification in the presence of two subscribing witnesses.
